CROSSING GATE

Carl O. Mericka, Chicago, and William M. Loser,
Wheaton, Ill., assignors, by mesne assignments,
to Consolidated Signal Company, a corporation of Illinois

Application May 9, 1930. Serial No. 450,991

14 Claims. (Cl. 39—7)

This invention pertains to crossing barriers, and more particularly to automatic and multiple safety gate and signal systems.

In safety barrier systems, the most satisfactory method of guarding a railway crossing, there are a number of problems which must be solved. First of all, an adequate crossing barrier must be provided which is positive in operation, affords adequate protection, and operates on the safety side, being preferably automatically controlled by the approaching track vehicle. Obviously, crossing barriers which are manually operated, even though the first cost may be less than that of an automatically controlled barrier, are more expensive in the long run since an attendant must always be at the crossing to raise and lower the crossing gates at the approach of a train, this attendant must be sheltered, and some means provided whereby the approach of the train is indicated to him. Another consideration is that the crossing gate must be as inexpensive as possible, for at least two gates must be installed at a crossing.

With the old type of gates, if a road vehicle is trapped between the lowered crossing gates, the road vehicle is either hit by the approaching train or must break through the crossing gate, causing damage to either the gate or the vehicle, or both, so that it is desirable that there be some safety feature connected with the gate whereby the gate can be rendered inoperative for a short period of time to take care of any emergency whereby a motorist is trapped between the gates when in lowered position, and this safety feature preferably should not involve the raising and lowering of the gates, as this is slow and opens the crossing where a train is approaching.

There are other contingencies which may arise which should be taken care of for the crossing gate to be successful, one of which is the condition wherein the gates may be lowered and strike, say, the upper portion of a road vehicle. This frequently occurs where the motorist approaches at too great a speed and so is not able to stop in time.

It is therefore an object of this invention to provide a barrier construction which, while effective to provide safety means at a crossing, is still yieldable under impact and/or obstruction.

A further object of this invention is to provide a crossing barrier which, though positive in operation, is operable in a manner whereby jarring of the barrier is prevented.

A still further object of this invention is to provide a crossing barrier system wherein a plu-

rality of means of operation is provided, one of which is normally inoperative and which is only operative upon failure of the normally operative means.

Yet a further object is to provide a barrier and system of operation therefor which fulfill all requirements of manufacture and service.

With these and various other objects in view, the invention may consist of certain novel features of construction and operation, as will be more fully described and particularly pointed out in the specification, drawings and claims appended hereto.

In the drawings, which illustrate an embodiment of the device and wherein like reference characters are used to designate like parts—

Figure 1 is a fragmentary, sectional elevation through the improved crossing barrier;

Figure 2 is a fragmentary, sectional elevation of the sidewalk or supplementary barrier adapted to be associated with and operable by the mechanism shown in Figure 1;

Figure 3 is a fragmentary side elevation of the crossing barrier illustrated in Figure 1, the same showing the barrier arms in operative or closed position, the dotted lines representing the barriers in raised or inoperative position;

Figure 4 is a fragmentary, top plan view of the construction shown in Figure 3;

Figure 5 is an enlarged, sectional elevation through the head or rotating portion of the pedestal, showing the barrier arms associated therewith, the same being taken substantially at ninety degrees to Figure 1;

Figure 6 is an enlarged, fragmentary sectional elevation of a portion of the operating mechanism or the supplementary barrier, the same being taken substantially at ninety degrees to Figure 2;

Figure 7 is an enlarged plan of the yoke and associated mechanism forming a yieldable operating means for emergency swing of the main barrier.

In the crossing barrier illustrated, the standard or pedestal 10 is provided with a base 12 having secured thereto the support 14 forming a foundation to which the D. C. motor 16 and the A. C. motor 18 are secured, the standard being provided with suitable cover plates 20 forming convenient means of ingress to the operating mechanism. The standard 10 is provided with the casing 22 having the ball race 24 for supporting the balls 26 providing anti-friction means between the race 24 and the race 28 provided in the support 30, the support 30 being secured to

the multiple tube 32 to which the head 34 is fixedly secured and around which the head is adapted to rotate. The casing 22 is preferably provided on the vertical center line or axis of the construction whereby a proper rotation of the head 34 may be effected and the standard 10 forms a support for the casing 36 secured thereto and resting thereon through the interfitting sections 38, the casing 36 forming a support for the sidewalk or supplementary barrier 40 operated through the support 42 secured to the casing 36. The support 42 at its outer end is provided with a casing 44 in which the gear 46 is mounted to rotate on the shaft 48, the shaft 48 being provided with the gear wheels 50 adapted to mesh with the racks 52 provided on the opposing sections constituting the sidewalk barrier 40, the racks being disposed in a suitable manner whereby ingress of foreign matter to the racks and pinions is prevented. The shaft 48 is adapted to be rotated by the pinion 54 meshing with the gear 46, the pinion being mounted on and operated by the shaft 56, said shaft extending through the bearing 58 provided in the casing 60, forming the connection between the casings 36 and 42, the inner end of the shaft 56 being provided with the gear 62 meshing with and adapted to be operated by the gear 64, said gear being mounted on the vertical shaft 66 journaled in the bearing 68 shown as carried by the casing 60, the shaft extending down and being journaled into the casing 70 as at 72. The lower end of the shaft 66 is provided with the reversible worm 74 meshing with the gear 76 for operation of the limit switches 78, said switches being described in detail in application Serial No. 476,578, filed August 20, 1930. The shaft 66 is also provided with the gear 80 meshing with and adapted to be operated by the gear 82 secured to the operating shaft 84 extending upwardly through the casing 22, the tube 32 and into the head 34, being journaled therein as at 86, the upper end of the shaft 84 being provided with the reversible worm 88 meshing with the gear 90 mounted on the shaft 92 suitably journaled in the head 34 as at 94 and provided at its outer ends with the gear wheels 96 adapted to mesh with the racks 98 provided on the sections forming the road barrier 100. The standard 10 is provided with a suitable stop 102 and a head may be provided with a suitable stop 104 adapted to limit the movement of the crossing barrier in raised and lowered position, and in a similar manner the sidewalk arm may be limited in its movement by means of the stop 106. The casing 32 is provided with a gear segment 108 meshing with the gear segment 110 mounted on the trunnion 112 secured to the casing 36. The gear 110 is provided with a hub 114 on which the yoke 116 is mounted, said yoke being provided with fittings 118 pivoted thereto as at 120 and providing securing means for the vertically extending threaded rods 122, said rods extending downwardly through suitable apertures in the floor of the casing 36, the ends of said rods being provided with the heads 124 between which and the floor of the casing is disposed coil compression spring 126. The barrier is, of course, suitably provided with flashing lights (not shown) operated by a flasher relay and the like, to be later described, and also may be provided with a suitable signal, such as a bell (not shown). The bell and the flashing lights are operated in a manner to be later described, the current being conducted thereto by means of a cable 128 extending from the head 34 downwardly through

the hollow shaft 84 to suitable connections to be later described, it being understood that both the A. C. and D. C. motors drive the shaft 84 through a suitable train of gearing connected to the pinion 130 mounted on the hollow shaft 84.

In operation, assuming the gate or barriers 100 and 140 to be in raised position as shown in the dotted lines in Figure 3, and assuming operation of, say, the A. C. motor 16, the motor will operate through a suitable train of gearing (not shown) to rotate the pinion 130 whereby the shaft 84 will be rotated, rotation of the shaft 84, of course, will operate the shaft 92 through the worm and gear 88-90 whereby the pinion 96 will be rotated to bodily move the gate 100 whereby the center of gravity of said gate will be shifted to a point to the left as viewed in Figure 1 with respect to the shaft 92, causing the barrier 100 to move downwardly. Rotation of the shaft 84 will also rotate the gear 82, in turn operating the gear 80 and the shaft 66, causing operation of the worm and gear 74-76 which is so proportioned that when the barrier 100 has reached its down position, the limit switch will be operated to cut off the current to the motor, causing the same to stop. Rotation of the shaft 66 causes rotation of the shaft 56 through the gears 64-62 whereby rotation of the shaft 48 is effected through the worm and gear 54-46. Rotation of the shaft 48 causes operation of the gear 50 whereby the gate 40 is bodily moved, shifting its center of gravity to lower said gate in a manner similar to the lowering of barrier 100. In the event that the barrier 100 is struck after it has reached its lowered position, as where an automobile is trapped between gates and seeks to run out of the gates, horizontal movement of the barrier is permitted. Movement of the barrier 100 causes rotation of the head 34 on the bearings 24-26-28, which causes the (torque) tube 32 to rotate whereby the gear segment 110 is rotated on the trunnion 112 by the gear segment 108. Rotation of the gear segment 110 causes the yoke to rotate, wherein one arm is raised and the other is lowered, depending upon the direction from which the gate is moved. Upward movement of one of the rods 122 will cause compression of its spring 126 between the head 124 and the floor of the casing 36, and when the barrier 100 is released, the spring will elongate, seeking its normal position, and the gate will be returned to its normal position blocking the roadway. A similar mounting for transverse movement may be made at the sidewalk arm 40 in the casing 44, but as side movement of the gate 40 should never occur, this construction is not illustrated.

Reversal of the motor operates the parts in a reverse direction causing overbalancing of the arm in another direction whereby it is moved to its upper or inoperative position. As before, when its upper position is reached, the limit switch operates to cause the motor to stop whereby the parts are in position awaiting further operation.

The gates may of course be operated manually or automatically through suitable circuits, and it is to be understood that we do not wish to be limited by the exact embodiment of the device shown, which is merely by way of illustration and not limitation, as various and other forms of the device will of course be apparent to those skilled in the art without departing from the spirit of the invention or the scope of the claims.

We claim:

1. In a crossing gate assembly, the combination

- of a support, a movable head thereon, a gate arm mounted for pivotal and bodily movement thereon, means for operating said arm, and means for yieldably maintaining said head in normal position, said means including a yoke. 5
2. In a crossing gate assembly, the combination of a support, a movable head thereon, a gate arm mounted for pivotal and bodily movement thereon, means for operating said arm, and means for yieldably maintaining said head in normal position, said means including a yoke, said yoke being provided with a plurality of springs yieldably maintaining said yoke in a predetermined position. 10
3. In a crossing gate assembly, the combination of a support, a movable head thereon, a gate arm mounted for pivotal and bodily movement thereon, means for operating said arm, a support on said first named support, and a gate arm mounted for pivotal and bodily movement thereon, said last named gate arm being operated by said means. 15
4. In a crossing gate assembly, the combination of a support, a movable head thereon, a gate arm mounted for pivotal and bodily movement thereon, means for operating said arm, a support on said first named support, and a gate arm mounted for pivotal and bodily movement thereon, said last named gate arm being operated by said means, said means being arranged to permit movement of said head without affecting movement of said last named gate. 20
5. In a crossing gate assembly, the combination of a support, a head thereon, a shaft secured to said head and mounted for rotary movement on said support, a yoke mounted adjacent and cooperating with said shaft, springs secured to said yoke and maintaining said yoke in predetermined position whereby movement of said head is resisted by said springs and returned to normal position by said springs. 25
6. In a crossing gate assembly, the combination of a support, a head thereon, a shaft secured to said head and mounted on anti-friction bearings for rotary movement on said support, a gear on said shaft, a yoke rotatably supported adjacent said shaft and having a gear meshing with said first named gear, springs connected to said yoke for maintaining said yoke in predetermined position whereby said springs return said head to predetermined position after movement thereof. 30
7. In a crossing gate, the combination of a pedestal having a gate mounted thereon for movement of translation, a movable head mounted on said pedestal, a gate mounted on said head for movement of translation, and means connecting said gates, whereby they are operated simultaneously. 35
8. In a crossing gate, the combination of a pedestal having a movable head mounted thereon, a barrier mounted for movement on said head, a rotatably mounted member mounted on said pedestal and provided with resilient means and cooperating with said head for maintaining said head in yielding predetermined position. 40
9. In a crossing gate, the combination of a pedestal having a support, a head, a member secured to said head and pivotally mounted on 45
- said support, a barrier mounted on said head, means for operating said barrier mounted in said pedestal and connecting means extending from said means through said member into said head whereby said head may be rotated independently of operation of said barrier. 50
10. In a crossing gate, the combination of a pedestal having a support, a head, a member secured to said head and pivotally mounted on said support, a barrier mounted on said head, means for operating said barrier mounted in said pedestal, connecting means extending from said means through said member into said head whereby said head may be rotated independently of operation of said barrier, and means resiliently mounted on said pedestal and cooperating with said member whereby said head is yieldably maintained in a predetermined position. 55
11. In a crossing gate construction, the combination of a pedestal, a gate arm mounted on said pedestal, a movable head mounted on said pedestal, means for normally maintaining said head in predetermined position, a gate arm mounted for movements of translation and rotation on said head, and means connecting said gate arms whereby said arms are operated substantially simultaneously. 60
12. In a crossing gate construction, the combination of a pedestal, a gate arm mounted on said pedestal, a movable head mounted on said pedestal, means for normally maintaining said head in predetermined position, a gate arm mounted on said head, and means connecting said gate arms whereby said arms are operated substantially simultaneously. 65
13. In a crossing gate, the combination of a pedestal, a head disposed thereon, said head being provided with a shaft extending into said pedestal and mounted for rotation therein, a jackshaft mounted on said pedestal, a yoke mounted on said jackshaft and having opposed compression springs for yieldably maintaining said yoke in predetermined position, gear members non-rotatably mounted on said yoke and shaft and meshing whereby said springs yieldably maintain said head in predetermined position, a gate arm mounted on said head, means for operating said gate arm mounted in said pedestal, and connecting means between said means and said gate arm including means extending through said shaft. 70
14. In a crossing gate, the combination of a pedestal, a head disposed thereon, said head being provided with a shaft extending into said pedestal and mounted for rotation therein, a jackshaft mounted on said pedestal, a yoke mounted on said jackshaft and having opposed compression springs for yieldably maintaining said yoke in predetermined position, gear members non-rotatably mounted on said yoke and shaft and meshing whereby said springs yieldably maintain said head in predetermined position, a gate arm mounted on said head for movements of rotation and translation, means for operating said gate arm mounted in said pedestal, and connecting means between said means and said gate arm including means extending through said shaft. 75
